UNITED STATES PATENT OFFICE.

WALTER D'A. RYAN, OF NORTH ADAMS, MASSACHUSETTS.

SYSTEM OF DECORATION.

1,211,239.

Specification of Letters Patent.

Patented Jan. 2, 1917.

Application filed December 18, 1913, Serial No. 807,566. Renewed November 13, 1916. Serial No. 131,146.

To all whom it may concern:

Be it known that I, WALTER D'A. RYAN, a subject of the King of Great Britain and Ireland and the Isle of Man, residing in 5 North Adams, Massachusetts, have invented certain Improvements in Systems of Decoration, of which the following is a specification.

One object of my invention is to provide 10 a novel combination of apparatus particularly designed to produce an ornamental, decorative effect in illuminating or outlining buildings or other objects, the various parts comprising said invention being of 15 such a nature as to be relatively inexpensive both as regards their first cost as well as their cost of operation.

Another object of the invention is to provide 20 a system having the characteristics above noted in which the reflecting and refracting elements shall produce an attractive, ornamental effect in the day time when acted on by sunlight, as well as at night when acted on by artificial light, the invention 25 contemplating such means for supporting these elements as will cause them to automatically act to produce a succession of different colored flashes or beams of light under the action of the wind or by reason 30 of the vibration of the structure on which they are mounted.

A further object of the invention is the provision of novel means for adjustably mounting the reflecting and refracting elements, as well as means whereby these may 35 be caused to give flashes or light beams of different colors in greater or less numbers and that at different angles and distances.

Another object of my invention is to provide 40 an artificial means of setting the jewels in vibration, such as the use of an air blast, vibrator or other electrical or mechanical means.

These objects and other advantageous ends 45 I secure as hereinafter set forth, reference being had to the accompanying drawings, in which:—

Figure 1 represents, to some extent diagrammatically, a portion of a building to 50 which my invention is applied; Figs. 2 and 3 are plan views illustrating diagrammatically certain arrangements of the light sources relatively to one of the reflecting

and refracting elements; Figs. 4 and 5 are diagrammatic side elevations illustrating 55 other arrangements of the light sources; Fig. 6 is a side elevation illustrating one of the jewel holders and its support; Fig. 7 is a front elevation of the holder shown in Fig. 6; Fig. 8 is a side elevation of another 60 form of jewel holder and its support; Figs. 9, 10 and 11 are plans illustrating different cut jewels which I may use as reflecting and refracting elements; Figs. 12, 13 and 14 are side elevations partly in section, illustrating 65 the cutting of the elements shown in Figs. 9, 10 and 11 respectively, and Fig. 15 is a perspective view of one device for causing the jewels to vibrate.

In carrying out my invention, I employ 70 a number of reflecting and refracting elements in the form of so-called jewels carefully cut from glass having a suitable index of refraction, and mounted to outline or to more or less closely cover the surface of a 75 building or other structure to which they may be applied. With this idea in view, the jewels may be cut according to any desired or suitable pattern such as, for example, those shown in Figs. 9 to 14 inclusive. 80 These jewels are mounted in settings or holders of which each of those shown in Figs. 6 to 8 consists of a length of wire having a circular body section 1, carrying three or more clips 2 formed of pieces of sheet 85 metal projecting both above and below the plane of the section 1.

One part of each clip is preferably bent into triangular form so as to receive the sharp edge of the jewel, while its opposite 90 end is bent inwardly to engage the under surface or back of the jewel. One end of the wire holder is bent at right angles to the plane of the circular section or body 1 to form an abutment or stop 3 to limit inward or rearward swinging and possible injury to the apex, while the opposite end is extended in one or more loops 4 and 5 in planes substantially parallel to that of the circular section. 95

For supporting each holder with its jewel 6, I provide a suspension member 7 having an eye 9 at one end for the reception of a pin, screw or nail 8 and at the opposite end formed in a second eye 10, preferably lying 105 in a plane substantially at right angles to

that of the eye 9. The length of the member 7 is such that when the loop 5 of one of the holders rests within its eye 10, the jewel 6 with its axial line (which extends from the center of its front table to its rear apex) is substantially co-incident with the line of the nail or pin 8 with the result that the work of mounting the jewels to form designs and letters would be materially facilitated. While for certain purposes the suspending member 7 is preferably employed, I may use a member ^{7a} of the form shown in Fig. 6, consisting of a relatively short length of wire or other suitable material so shaped that the eye 9 for the reception of the nail or pin 8 projects above the eye 10 for the reception of the jewel holder.

When acted on by a number of rays of light emanating from a source thereof so distant that said rays are either actually or substantially parallel, the jewels 6 which have the cutting shown in Figs. 11 and 14, project flashes or pencils of light having the various colors of the spectrum. If cut as shown at ^{6a} in Fig. 9, the jewels, under the conditions above noted, produce flashes or pencils of white light emanating from various parts of its surface, while if cut as indicated at ^{6b} in Fig. 10, they apparently produce rings of light.

I preferably make the jewels of different colored glasses and as a consequence they may be colorless to represent the diamond or may have the colors of the various other precious stones.

In utilizing the jewels above described in carrying out my invention, I employ holders such as those shown in Figs. 6 to 8, with suspending members preferably of the type shown in Fig. 8. With the aid of these devices, I mount the jewels at distances of say four or five inches apart around the edges of a building and along various cornices or portions thereof which it is desired to emphasize or display, it being understood, of course, that if desired the jewels may be mounted in solid masses or may be disposed upon a building or any other supporting structure in various ornamental forms or figures.

In the case illustrated in Fig. 1, I have indicated, to a great extent diagrammatically, a tower having lines of jewels extending along both sides of each of its vertical edges and across certain of its cornices, and since with the holders shown, said jewels are free to swing or vibrate in all directions with the greatest freedom, particularly in a vertical plane including the body of the suspending member 7, the rays of the sun striking said jewels are reflected and refracted so as to produce a rapid succession of light flashes having different colors, etc., depending upon the cutting employed. Moreover, these flashes or beams apparently vary in

size depending upon the distance of the observer from the jewels, it being a noticeable fact that at certain distances the flashes appear to emanate from light sources many times larger than the jewels themselves.

While in Figs. 6 and 8 I have shown the jewels as mounted in holders which support them with their axial lines substantially horizontal, it is to be understood that under conditions of use such holders would either so hang as to incline downwardly the plane face or front table of each jewel, or the said holder would be adjusted by being bent at 11 or at any other suitable point, to attain this same end. Thus in a building or tower such as shown in Fig. 1, the jewels at the top and upper portions thereof would have their longitudinal axes directed downwardly at some predetermined angle to the horizontal, while the holders of those jewels adjacent the lower portions of the tower would be adjusted so that their longitudinal axes would be more nearly horizontal, with the result that all of the jewels would produce their maximum effect on an observer at a predetermined distance from them.

While a building or other structure having jewels mounted as above described would present a most attractive and ornamental appearance during the day time and particularly when exposed to the direct action of the sun's rays in the morning or afternoon, I preferably provide means whereby said jewels are rendered active at night, and with this idea I mount any desired and suitable number of projectors or searchlights 12 at suitable distances from the structure on which the jewels are supported, directing the light therefrom upon said jewels. Inasmuch as the projector or projectors should preferably be mounted at a considerable distance from the jewels which it is to illuminate, the rays of light emanating from the same are to all intents and purposes parallel. When illuminated by light from such a source or sources the jewels are particularly effective and when supported as above described, produce large intermittent light flashes by reason of their own vibration as well as because of the voluntary and involuntary changes of position of the eyes of the observer. It will be understood that a maximum number of flashes from any one jewel illuminated from a single source, will be obtained by an observer stationed immediately adjacent such source of light or adjacent a line between the source and the jewel, and where a number of light sources are employed the number of flashes from a jewel is also directly proportional to the number of such sources directed upon it.

If desired, I may group a number of projectors 12, ^{12a} and ^{12b} close together as shown in Fig. 3 and direct their light over approximately the same area. In such case,

while an observer stationed anywhere in front of a jewel 6 would receive a number of light flashes therefrom, the greatest number of these would be received by one adjacent the projectors or somewhere in the line between them and the jewel. On the other hand, as shown in Fig. 2, the projectors may be more or less widely separated so that the angle of activity of the jewels is increased over that of the case shown in Fig. 3, with the result that a larger number of light flashes would be received by an observer anywhere within a large area in front of the jewel 6.

10 In order to vary the disposition and number, as well as the intensity of the light flashes received from a given jewel or set of jewels, I may arrange the projectors, as shown in Fig. 4, all in substantially the same horizontal plane but at widely differing distances from the jewels, or again, I may arrange the projectors vertically one above the other and at considerable distances apart. In the case shown in Fig. 4 the angles of inclination of the various jewels or sets of jewels may be adjusted so that the rays of light from each source thereof will strike the jewels of any particular set in lines substantially normal to their tables.

15 Under conditions of operation, I alter at will the color of the light directed upon the jewels, which may be either colorless or colored, and for example, if a red light be projected, the light emitted by the jewel gives the latter the effect of a ruby. Obviously other colors or combinations thereof may be employed as may be desired. If it should be desirable to vary the activity of the jewels under the action of the sun's rays, the holders or supporting members may be adjusted to vary the angle of the plane of the tables of the jewels to the horizontal. For instance, if it is desired that the jewels shall be relatively active at a distance of half a mile, the inclination from the vertical of the planes of their tables would be relatively slight.

20 It is to be noted that while I have shown nails as used to attach the jewel-supporting members to the building or other supporting structure, it is obvious that screws or other forms of holding devices may be used for this purpose, without departing from my invention, as being the equivalent of nails. Especially when the jewels are used for interior decoration, I may provide some means for setting them into vibration or for causing them to continuously vibrate, as for example, I may direct a blast of air on to the jewels or may provide some mechanical device whereby they will be vibrated or otherwise moved in order to accomplish the same object.

I claim:

1. A decorative system consisting of a

supporting structure; a series of jewels movably mounted thereon; and a series of relatively distant projectors mounted to illuminate said jewels.

2. A decorative system consisting of a 70 supporting structure; a series of colored freely movable, pendant jewels mounted thereon; with a relatively distant means for projecting a beam of light on said jewels.

3. A decorative system consisting of a 75 supporting structure; a series of colored freely movable, pendant jewels mounted thereon; with a relatively distant means for projecting a beam of colored light on said jewels.

4. The combination of a supporting structure; a jewel-carrying member mounted thereon; a jewel having a rearwardly extending conical portion; a holder for the jewel suspended from said member; with a 85 projection on the holder extended in position to strike the supporting structure before it can be engaged by the rearward extension of said jewel.

5. As a new article of manufacture, a 90 jewel and a holder therefor provided with a suspending portion having a rearward projection for limiting its rearward swing.

6. As a new article of manufacture, a 95 jewel and a holder therefor consisting of suspending and body portions; means for rigidly connecting said body portion to the jewel; and a projection for limiting the rearward movement of the jewel.

7. The combination of a jewel with a 100 holder therefor consisting of a wire having a substantially circular portion formed to receive the rear part of the jewel, one end of said wire being extended to form a suspending portion and the other end being projected substantially at right angles to the plane of the jewel-receiving portion to form a stop; with clips on the jewel-receiving portion formed to hold a jewel therein.

105 8. The combination in a decorative system of a supporting structure; a series of jewels movably mounted thereon; and suspending means for said jewels including flexible portions capable of being bent to vary the 115 angle of the axes of said jewels to the horizontal.

9. The combination in a decorative system of a supporting structure; jewels mounted on said structure; and relatively distant 120 means for projecting substantially parallel rays of light on said jewels, the jewels on the upper portions of the supporting structure having their axes inclined at a greater angle to a horizontal plane than those on 125 the lower portion thereof.

10. The combination of a supporting structure; a suspending member; a nail connecting said member with the supporting structure; a jewel holder movably suspended 130

from the said member; and a jewel carried by the holder with its axis substantially coincident with the axis of the nail.

11. The combination of a supporting structure; a suspending member consisting of an upwardly extending overhung body of material; a nail connecting said member with the supporting structure; a jewel holder movably depending from said member; and a jewel carried by said holder with its axis substantially coincident with the line of the nail.

12. The combination of a building structure; and a series of pendant freely movable faceted jewels carried thereby in positions to outline the same.

13. The combination of a supporting structure; a series of freely movable jewels mounted thereon; with means for causing said jewels to vibrate. 20

14. The combination of a supporting structure; a series of freely movable jewels mounted thereon; a source of light for illuminating the jewels; with means for causing said jewels to vibrate. 25

In testimony whereof, I have signed my name to this specification, in the presence of two subscribing witnesses.

WALTER D'A. RYAN.
